EDWIN W. STONE, OF LONGMEADOW, MASSACHUSETTS, ASSIGNOR TO BIGELOW-SAN-FORD CARPET CO., INC., OF THOMPSONVILLE, CONNECTICUT, A CORPORATION OF MASSACHUSETTS

TAKE-UP MECHANISM FOR LOOMS

Application filed November 28, 1928. Serial No. 322,379.

This invention relates to looms and is more particularly directed to mechanism for taking up the cloth as it is woven.

It is now the ordinary practice to provide looms with a take-up mechanism at one side thereof for driving a take-up roll over which the fabric passes, and such mechanisms have been effective in taking up the cloth during the weaving operation where the loom itself has not been of unusual width. During recent years, however, there has been a constantly increasing demand for wider and wider fabrics, especially heavy fabrics such as carpets, rugs and the like, and in answering this demand problems have arisen with respect to the cloth take-up mechanism due to the usual length of the take-up roll which is liable to partake of a torsional displacement or twist when driven at one end.

In accordance with the present invention, the take-up roll is driven at both ends by trains of mechanism each of which includes a worm and worm wheel connection between the ends of the take-up roll and the actuating mechanism. It may happen at times, however, that the take-up roll is to be reversely turned to let-back and thereafter restored to its take-up position, or one of the trains of mechanism may become functionally inoperative at times; wherefore the present invention further provides a one-way or flexible connection between the worm wheels at each side of the loom and the ends of the take-up roll, all of which will be more fully disclosed by the following description and the accompanying drawings of one good, practical form of the invention.

In the drawings:

Fig. 1 is a perspective view of a wide loom for weaving heavy fabrics such as carpets, rugs and the like, and provided with the present invention;

Fig. 2 is a section longitudinally of the take-up roll, showing more particularly the

one-way drive connection between the worm wheel and take-up roll;

Fig. 3 is a detached detail showing one form of ratchet and pawl mechanism for actuating the worm;

Fig. 4 is a sectional elevation showing a modified form of the invention;

Fig. 5 is a sectional front elevation showing the modified form of drive between the worm wheel and take-up roll; and

Fig. 6 is a section on the line 6—6 of Fig. 4.

The loom frame may be of any usual construction and as shown comprises the side frames 1 between which is mounted the lay 2 having the reed 3 through which pass the warp threads 4, it being understood that the warp threads are themselves controlled and separated for the shedding operation by suitable shedding mechanism which, however, forms no part of the present invention.

Mounted in suitable bearings 5, one at each side of the loom, is the take-up roll 6, which may be of the spike type the axis of which at each side of the loom extends outwardly, as indicated in Fig. 2, and loosely mounted on a portion 7 of the take-up roll axis at each side of the loom is a worm wheel 8 which meshes with a suitable worm 9 secured for rotative movement upon the worm shaft 10 which may be conveniently supported in suitable bearings 11, as indicated in Fig. 1.

The worm shaft 10 has secured thereto a gear 12 which may be driven by a train of mechanism actuated from a going part of the loom. In the form of the invention indicated by Fig. 1, the gear 12 is in mesh with a gear 13 mounted in one of the brackets 11 and itself driven by a gear 14 mounted upon the shaft 15, the relative sizes of the gears being such as to impart to the worms 9 at each side of the loom the desired speed to be transmitted to the take-up roll, as will presently appear.

Secured to the shaft 15, Fig. 1, is the ratchet wheel 16 which may be actuated step-by-step by a pawl 17 mounted upon the pawl carrier 18.

18 and loosely supported about the axial center of the shaft 15. The pawl carrier 18 has connected thereto the link 19 which is given its actuating movement, as shown in Fig. 1, by a lever 20 pivotally mounted at 21 to the side frame of the loom and connected at its rear end to a bell crank lever 22 supported for rocking movement on the stud shaft 23. In the present instance of the invention, as indicated in Fig. 1, the rear end of the lever 20 is provided with a pin 24 which engages a slot 25 in the bell crank lever 22, and the latter itself may be given its rocking movement through a link 26 from any suitable going part of the loom, the construction being such that as the lever 20 is actuated, as hereinbefore described, the pawl 17 will turn the ratchet wheel 16 step-by-step to thereby impart rotative movement to the worm 9 through the train of mechanism described. To prevent retrograde movement of the ratchet wheel 16 a holding pawl 27 is pivoted on a pin 28 carried by a bracket arm 29.

The train of mechanism for actuating the worm and through it the loose worm wheel 8 at each side of the loom may, however, be modified, the essentials in this respect being that during weaving the worm and worm wheel 8 operatively connected to the worm shall be given their operating movements.

As hereinbefore stated, the present invention contemplates a one way power transmission connection between each of the worm wheels 8, one at each side of the loom, and the take-up roll.

As shown in Figs. 1 and 2 of the drawings, such one way power transmission connection comprises a ratchet wheel 30 secured to each end of the take-up roll 6 and circumferentially related to the ratchet wheel 30, as shown, and each of the worm wheels 8 is provided with a pawl carrying portion 31 in which is mounted a series of pawls 32 for engagement with the ratchet teeth of the ratchet wheels 30.

Obviously there may be any number of pawls 32 but since heavy fabrics, such as carpets, rugs and the like are to be woven, it is desirable that there be a plurality of pawls 32, the opposite pawls being so related to the ratchet wheel 30 as to be in actuating engagement therewith, while the remaining pawls of the series may remain inactive, as indicated in Fig. 1. Each of the pawls 32 may comprise a toothed portion 33 and an upwardly extending stem 34 about which is mounted a spring 35 normally acting to move the pawls inwardly into operative engagement with the teeth of the ratchet wheel 30.

As more clearly shown in Fig. 1, two of the pawls, one above and one below the take-up roll 6, are operatively engaged with the teeth of the ratchet wheel, while the remaining pawls are idle. By this construction it will be apparent that should the take-up roll 6 be

turned slightly in a forward direction, one or more of the pawls will be operatively engaged with the teeth of the ratchet wheels, thereby obviating any substantial lost motion.

Each of the ratchet wheels 30, one at each end of the take-up roll, may be secured to the roll by any appropriate means, but as shown they are secured to the take-up roll by a key 36, although, of course, this manner of securing the parts together for turning movement in unison may be variously contrived.

From the construction described it will be apparent that upon actuation of the worms 9, one at each side of the loom, the associated worm wheel 8 will be turned and through the one way power transmission between the worm wheels 8 and the ends of the take-up roll, the latter itself will be correspondingly turned to take up the cloth *a* during the weaving operation.

The invention as described provides a positive drive for each end of the take-up roll which obviously may be of the sand or spike roll type, with the result that all torsional twist of the take-up roll under the heavy stress of the fabric will be avoided.

As hereinbefore noted, it may happen at times that the cloth *a* is to be let back by reverse rotative movement of the take-up roll and then restored to position the fell of the cloth for the lay beat-up, or one of the take-ups may become functionally ineffectual at times. In either event and notwithstanding that the take-up roll is actuated through a worm and worm wheel at each end, rotative movement of one at either side of the loom will serve to take up the cloth by reason of the one way power transmission between the worm wheels 8 and the ends of the take-up roll.

Mounted upon the worm shafts 10, one at each side of the loom, is a hand wheel 37, whereby the cloth roll 6 may have let-back movement imparted thereto by hand manipulation upon disengagement of the pawls 17 and 27 from their associated ratchet wheels 16. Similarly, the take-up roll may be given its take-up movement from either side of the loom through the hand wheel 37, by reason of the one way power transmission connection between the worm wheels 8 and the take-up roll.

Thus it will be obvious that the present invention not only provides for a positive drive for the take-up roll at each end thereof through a worm and worm wheel connection which acts as a lock as usual, but should either of the drive mechanisms fail to function at any time the take-up roll may be actuated by the other, notwithstanding the worm and worm wheel drive and lock at each end of the roll.

In the form of the invention shown and described with respect to Figs. 1, 2 and 3,

the drive for the ends of the take-up roll has been through a ratchet and pawl mechanism and a one way power transmission has been effected through a ratchet wheel and cooperating pawls, but such features may be modified, as shown by Figs. 4, 5 and 6, though functionally operating to the same end.

In the modified form of the invention, the take-up roll 6 has loosely mounted thereon at each end a worm wheel 8, as hereinbefore described, and mounted upon the worm wheel 8 is a toothed member 38 which may be appropriately secured to the associated worm wheel 8 by bolts or similar means 39, as indicated in Fig. 5. The toothed member 38 has a series of teeth 40 extending radially thereof to a more or less degree, and associated therewith is the opposed toothed disk 41 similarly provided with radial teeth and mounted on the end of the take-up roll at each end thereof for rotative movement therewith. In the present instance, as shown in the modified form of the invention, the end portions of the take-up roll 6 are slabbed off, as at 42, Fig. 6, to engage a corresponding opening in the toothed disk 41 whereby the latter is caused to be connected to the take-up roll for rotative movement therewith, and interposed between a collar 43 at each end of the take-up roll and the toothed disks 41 is a spring 44 normally tending to hold the teeth of the two disks 38 and 41 in operative engagement but with permissive give-way, thus constituting a flexible connection for one way power transmission.

As previously described with respect to Figs. 1, 2 and 3, each of the worm wheels 8 is operatively engaged with a worm 9 mounted on the worm shaft 10 which may be driven through a train of mechanism 45, 46 and 47. In the modification as indicated in Figs. 4 and 6, the gear 45 is secured to the worm shaft 10, previously described, and is in operative engagement with a change gear 46 which may be suitably supported in adjusted position upon a bracket 48. The change gear 46 meshes with the gear 47, Figs. 4 and 6, which is itself loosely mounted on a power transmission shaft 49. Extending from the gear 47, Fig. 4, is a hub or sleeve portion 50 carrying at one end a clutch member 51, and splined for sliding movement upon the power transmission shaft 49 is the complementary clutch member 52. The clutch member 52 is controlled with respect to its operative or inoperative relation with the clutch member 51 by means of a shift-lever 53 pivoted at 54 and upon a suitable supporting bracket, the construction being such that when the clutch members 51 and 52 are engaged, the shaft 49 will transmit rotative movement to the connected worm 9, and when the clutch members are disengaged the worm 9 at each side of the loom remains idle.

The power transmission shaft 49 may be conveniently driven from a going part of the loom and, as indicated in Fig. 4 said shaft has secured thereto the worm wheel 55 which is engaged with the worm 56 mounted upon a shaft 57 for rotative movement therewith during the loom operation.

Each of the worm shafts 10, one at each side of the loom, is provided with a hand wheel 37 as previously described with respect to Figs. 1, 2 and 3, whereby the take-up roll may be turned by hand in a forward direction to take up the cloth when the clutch members 51 and 52 are disengaged.

The modified form of the invention as described differs mainly from the mechanism shown and described in Figs. 1, 2 and 3 in that the one way power transmission between the take-up roll and the associated worm wheels 8 is modified as described, and the train of mechanism for operating the worms 9 is modified as hereinbefore noted.

In both forms of the invention, however, the take-up roll 6 is driven at each end thereof through a worm and worm wheel and one way power transmission device, and in both cases when the actuating mechanism driven from a going part of the loom is made inoperative either by disengaging the pawls 17 and 27, or disconnecting the clutch members 51 and 52, the take-up roll may be turned at either side of the loom to take up the cloth. Similarly, should either one of the drive connections become functionally inoperative the take-up roll may be driven by the other drive mechanism, notwithstanding the worm and worm wheel connection at both ends of the take-up roll.

What is claimed is:

1. In a take-up mechanism for wide looms, the combination of a take-up roll, a positive take-up drive at each end of the take-up roll comprising driving means operated from a going part of the loom and gearing connections therewith for operating the roll at each end to take-up the cloth as it is woven, a one way operative connection between each take-up drive and the adjacent end of the take-up roll, and means associated with said positive take-up drive for manually rotating the take-up roll.

2. In a take-up mechanism for wide looms, the combination of a spike take-up roll over which the cloth passes, a positive take-up drive at each side of the loom comprising driving means operated from a going part of the loom and gearing connections therewith for driving the spike roll at each end, a one way operative connection between each positive take-up drive and the adjacent end of the spike roll, and means associated with said positive take-up drive for manually rotating the take-up roll.

3. In a take-up mechanism for wide looms, the combination of a spike roll over which

the cloth passes, an independent positive drive for each end of the spike roll comprising driving means operated from a going part of the loom and gearing connections therewith, a one way power transmission device between each positive drive and the adjacent end of the spike roll permitting the spike roll to be turned in one direction by either of the positive drives, and means associated with at least one of said positive drives for manually rotating the take-up roll.

4. In a take-up mechanism for wide looms, the combination of a take-up roll to take up the cloth during weaving, a positive drive for each end of the take-up roll including driving means operated from a going part of the loom, and a worm and a worm wheel connection therewith for driving the take-up roll to take-up the cloth as it is woven, a one way power transmission device between each positive drive and the adjacent end of the take-up roll that the latter may be driven by either or both of the positive drives, and means associated with said positive drive for manual rotation of the take-up roll.

5. In a take-up mechanism for looms, the combination of a take-up roll, a worm wheel loosely mounted on each end of the take-up roll, a worm in continuous operative engagement therewith for positively driving each of the loosely mounted worm wheels to take up the cloth as it is woven, and a one way power transmission device between each worm wheel and the take-up roll that the roll may be turned in one direction by either of the worm wheels while the other remains idle.

6. In a take-up mechanism for looms, the combination of a take-up roll, a worm wheel loosely mounted on each end of the take-up roll, a worm in continuous operative engagement with each worm wheel for positively driving each of the loosely mounted worm wheels to take up the cloth as it is woven, and a ratchet and pawl connection between each worm wheel and adjacent end of the take-up roll that the latter may be turned by either worm wheel to take up the cloth while the other remains locked by its worm.

7. In a take-up mechanism for looms, the combination of a take-up roll, a worm wheel loosely mounted on each end of the take-up roll, a positively operated worm in continuous engagement with the adjacent worm wheel for positively driving each of the loosely mounted worm wheels to take up the cloth as it is woven, a ratchet wheel secured to each end of the take-up roll, ratchet wheel to each end of the take-up roll, ratchet wheel

engaging means carried by each of the worm wheels and locking the worm wheels to the ratchets for turning the take-up roll at each end in one direction, and means for positively driving each worm from a going part of the loom.

8. In a loom, the combination of a take-up drive at each side of the loom, a spike roll, a worm wheel loosely mounted on each end of the spike roll, a worm at each side of the loom continuously engaged with the adjacent worm wheel, means for positively driving each worm to take-up the cloth as it is woven, a toothed member secured to each end of the spike roll for rotative movement therewith, a cooperating toothed member carried by each of the loosely mounted worm wheels and constituting a one way power transmission connection that the take-up roll may be driven by the drive at one end should the drive at the other end become functionally inoperative.

9. In a take-up mechanism for looms, the combination of a take-up roll, a ratchet wheel secured to each end of the take-up roll, a worm wheel loosely mounted on each end of the take-up roll, a worm at each side of the loom for driving each of the loosely mounted worm wheels, means including gearing connections with a going part of the loom for positively driving each worm to take-up the cloth as it is woven, and means connected to each of the worm wheels for engaging the adjacent ratchet wheel for driving the take-up roll at each end in a frontward direction.

10. In a take-up mechanism for looms, the combination of a take-up roll, a ratchet wheel secured to each end of the take-up roll, a worm wheel loosely mounted on each end of the take-up roll, a worm at each side of the loom in continuous driving connection with the worm wheels for positively driving each of the loosely mounted worm wheels to take up the cloth as it is woven, means for positively rotating each worm from a going part of the loom, and a series of pawls carried by each of the loosely mounted worm wheels and acting upon the ratchet wheels in cloth take-up direction only to drive the take-up roll at both ends and permit take-up movement of the roll by one end drive should the other be functionally inoperative.

11. In a take-up mechanism for looms, the combination of a take-up roll, a positive take-up drive at each end of the take-up roll comprising driving means operated from a going part of the loom for operating the roll at each end to take-up the cloth as it is woven, a one-way operative connection between each take-up drive and the adjacent end of the take-up roll, and manually operable means associated with each positive take-up drive for manually rotating the roll from either side of the loom.

12. In a take-up mechanism for looms, the combination of a take-up roll, a worm wheel loosely mounted on each end of the take-up roll, a one-way driving connection between each worm wheel and the adjacent end of the take-up roll, a worm at each side of the loom

in continuous driving engagement with the adjacent worm wheel, means for positively rotating each worm from a going part of the loom for operating the roll at each end to take-up the cloth as it is woven, and a hand wheel associated with each worm for manually rotating the roll from either side of the loom without disconnecting the positive drives for the worms.

10 In testimony whereof, I have signed my name to this specification.
